FRANK H. DUKESMITH, OF BUFFALO, NEW YORK, ASSIGNOR, BY DIRECT AND MESNE ASSIGNMENTS, TO THE UNITED STATES AIR BRAKE CORPORATION, OF BUFFALO, NEW YORK, A CORPORATION OF NEW YORK.

FLUID-PRESSURE-MAINTAINING SYSTEM.

1,081,526.

Specification of Letters Patent.

Patented Dec. 16, 1913.

Application filed November 27, 1912. Serial No. 733,856.

To all whom it may concern:

Be it known that I, FRANK H. DUKESMITH, a citizen of the United States, residing at Buffalo, in the county of Erie and 5 State of New York, have invented certain new and useful Improvements in Fluid-Pressure-Maintaining Systems, Particularly for Use in Connection with Railway-Air-Brake Cylinders.

10 The following I declare to be a full, clear, and exact description of my invention, such as will enable others skilled in the art to which it appertains to make and use the same, reference being had to the accompanying drawings, and to figures of reference marked thereon, which form part of this specification.

Like figures refer to like parts.

My invention relates to a system of 20 valves and other devices adapted to operate automatically to rebuild pressure in a brake cylinder or other device when leakage occurs to reduce pressure.

The object of my invention is to provide 25 a system of means for automatically releasing air or other fluid under pressure from its source into channels connected with a brake cylinder or other device to restore pressure lost by leakage.

30 A further object is to automatically shut off the source of pressure during exhaust from the said cylinder or other device and prevent the compressed fluid from wasting at that time.

35 My invention is actuated by slight changes from the full active pressure initially used in each instance of setting the brakes, regardless of what that pressure may be. Among other things, I provide a valve 40 mechanism having two chambers with a flexible wall between them. One of the chambers I designate as the variable pressure chamber, which being in open communication with the brake cylinders at all 45 times has within it the same pressure as obtains in said cylinders. The other chamber I style the control chamber wherein the air under the said full active initial pressure is stored and held there by a check valve.

50 As soon as the pressure in the variable chamber becomes reduced, the stored pressure in the control chamber distends the flexible wall and thus automatically furnishes a forcible means for opening a valve connected

with a source of fluid pressure, releasing 55 the same to rebuild the pressure lost by leakage.

Details of arrangement and construction of the means employed in connection with the two chambers just described are illustrated in the accompanying drawings, showing two modifications of my invention as employed in connection with an ordinary railway air brake equipment. Following a detailed description of the parts illustrated, 60 the operations of the same, for various conditions of pressure in the brake cylinder, are explained and what I claim is set forth.

Figure 1 is a diagrammatic illustration of an ordinary railway air brake equipment 70 in connection with one form of my system of valves shown in section as a compound valve. Fig. 2, is similar to Fig. 1, except that it shows a modified form of my system of valves in connection with said equipment. 75 Fig. 3, is a top plan of an engineer's automatic brake valve with attachments including an exhaust valve. Fig. 4 is a horizontal section of the compound valve taken on the line X—X of Fig. 1. 80

In Fig. 1, the principal features of an ordinary railway air brake equipment are shown as follows:—1 is an engineer's automatic brake valve connected by pipe 2 to the main reservoir 3, to which is connected a 85 pump 4. Also connected with the valve 1, is the pipe 5, in connection with the train pipe 6. A branch pipe 7 connects the triple valve 8 with the train pipe 6. Connected with the triple valve 8 by the pipe 8^a is the 90 auxiliary reservoir 9. 8^b is an exhaust pipe on the triple valve 8. Brake cylinders 10 and 11, by means of the pipe 12, are connected with the triple valve 8. A T 13 is in the line of pipe 12. Interposed in continuous connection between the auxiliary reservoir 9 and the T 13, are the pipe 14, the check valve 15, having a hinged disk 16, adapted to close a port 16^a, a supplemental reservoir 17, the pipe 18, the compound valve 19, and the 100 pipe 20. In the sectional view of the valve 19, under the cap 21 is a control pressure chamber 22, separated by a diaphragm 23 from a variable pressure chamber 24. Rings 23^a and 23^b hold the diaphragm 23 105 in position. Depending from the diaphragm 23 is the cone 25, held thereon by the disk 25^a and the nut 25^b. Within the

lower end of the cone 25 is loosely fitted a 5 stem 26, which is connected with a disk 27. This disk is shown closed against a valve seat 28, being normally held in this position by the spring 29, through which passes the stem 30. The stem 30 is adapted to reciprocate in the hole 31 and when down it closes communication with the passage 32. Leading from the chamber 33 to the chamber 34 10 is the passage 35. Below the chamber 33 is a valve seat 36, the port of which is adapted to be closed by a piston disk 37, but is held normally open by the spring 38; the disk 37 being adapted to reciprocate as a 15 piston within the cylindrical portion 39 of the valve 19. A small passage 40 is provided through the piston disk 37. The lower end of the valve 19 is closed by the cap 41, in the center of which is a passage 42 in communication with the piping 18. Through the raised portion of the cap 41, in contact with the piston disk 37, is a hole 43. In the upper left hand corner of the compound valve 19 is a check valve having a 20 chamber 44 in which is a disk 45, adapted to close a port in the valve seat 59, which is a continuation of passage 46, which passage is in communication with the variable pressure chamber 24. The stem 48 of the disk 25 45 is adapted for reciprocation within the cap 47. A spring 49 within the cap 47 holds the check valve normally closed. In the chime of the cap 21 are holes 50, 51, which form with the passage 52, free communication 25 between the chambers 44 and 22. In the upper right hand corner of the chamber 24 is a differential check valve having a valve seat 53, through which is a passage 54 communicating with the chamber 22. 30 Adapted to close the port in the valve seat 53 is the disk 55 on the stem 56, which is adapted to reciprocate within the cap 57. A spring 58 holds the valve normally closed. The area of the valve seat 53 in contact with 35 the disk 55 is several times larger than the area of the port it closes. In this Fig. 1, the valve 1 has a handle 61 and a top flange 76 correspondingly numbered to what is shown in Figs. 2 and 3.

40 In Fig. 2, a similar set of valves, reservoirs and connections to those described for Fig. 1, is illustrated and like parts are respectively numbered. The compound valve 19^a is similar to valve 19 with the exception that it has no differential check valve. The engineer's automatic brake valve 1^a, shown in this figure, has a handle 61. A bracket 62 is attached to the casing of the valve 1^a. Fulerumed in the bracket 62 is the lever 63 having a free beveled end 63^a adapted to engage, at times, the handle 61. Pivoted to the lever 63 is a yoke 64. Depending from the yoke 64 is a stem 65 of an exhaust valve 60 shown in section. The stem 65 passes down through a cap 66, then through

a chamber 67 and a valve seat 68 into a chamber 69. A disk 70, adapted to close a port in the seat 68, is fixed upon the stem 65. A spring 71 is adapted to hold this valve 60 normally closed. The lower end 70 of the stem 65 fits into a hole 72 in the casting of this check valve. A pipe 73 connects the passage 21^a of the valve 19^a with a passage 74 leading into the chamber 69. A passage 75 in the cap 66 affords an outlet 75 from the chamber 67 to the atmosphere.

In the top plan of the valves 1^a and 60 illustrated in Fig. 3, the lever 63 is shown with a curved portion concentric with the turning point of the lever 61. In the top flange 76 are five notches 77, 78, 79, 80 and 81, each of which respectively locates the handle 61 in one of the five positions of the engineer's automatic brake valve. It will be seen from this Fig. 3, that in only two 80 positions, that for notch 81 and that for notch 80, where the handle is shown in dotted position 61^a, can the lever 63 be engaged and depressed to open the valve 60.

In Fig. 4, the position of the hole 40 in 90 the piston disk 37 and the hole 43 underneath the disk 37 are shown.

In the form of my invention shown in Fig. 1, compressed air from the auxiliary reservoir 9 is free to pass the port 16^a of the check valve 15, raising the disk 16 and passing into the supplemental reservoir 17, 95 charges the same.

Instead of connecting the check valve 15 with the reservoir 9, connection might be 100 made direct with the train pipe 6, as the source of fluid pressure. In either case the check valve 15 will prevent the back flow from the reservoir 17. Air under pressure from any other source, as the main reservoir 3 or the pump 4, might be passed through the check valve 15 instead of from the auxiliary reservoir 9.

Air from the supplemental reservoir 17 is free to pass through the pipe 18 into the 110 passage 42, between the cap 41, and the piston disk 37, and thence through the hole 43 into the passage 40 of the piston disk 37 and over the top of the same into the port 36, the chamber 33, the passage 35 and into the chamber 34, at the same time air is passing through the passage 32 into chamber 33; the port 36 being normally open, on account of the piston disk 37 being held away from it by the spring 38, and the port in valve seat 28 being normally closed by the spring pressed disk 27. The hole 40 is made comparatively small, being only large enough to allow sufficient air to pass it to compensate for ordinary leakage in the 115 brake cylinders.

The variable pressure chamber 24 being in free communication at all times, with the brake cylinders 10 and 11, through the pipes 20 and 12 air under the full active initial 120 130

pressure used in setting the brakes passes through the channel 46 raising the spring pressed disk 45, enters the chamber 44, the channel 52, the holes 50 and 51 and the chamber 22. In communication with this chamber 22 is the channel 54, closed by the spring pressed disk 55, but in as much as the disk 55 is exposed freely to the pressure in the chamber 24, it will remain closed during the equalization of pressure in the two chambers 22 and 24, at the time of the presence of said full active initial pressure. On account of the equalization of pressure on both sides of the flexible diaphragm 23 there will be no movement of the same and the disk 27 will remain normally against its seat 28. Air at the said initial pressure will now remain stored in control chamber 22 until released through the valve seat 53. The area of the seat 53 being large compared with the port therein of the channel 54, a considerable reduction in pressure in the chamber 24 will be necessary to effect the opening of this valve to release the pressure in the chamber 22. Therefore for slight reductions of pressure in the chamber 24, there will remain the said initial pressure to force the diaphragm 23 down when the difference in pressure on the two sides of the same is sufficient to force the disk 27 off its seat and allow air under pressure to rebuild that which had become reduced in the chamber 24, and when this pressure has been restored, the diaphragm 23 will, on account of the condition of equalized pressure or nearly so, in the two chambers 24 and 22, take its normal position and the disk 27 will again become normally seated, closing off the air from the supplemental reservoir 17. In thus restoring pressure within the chamber 24, air is supplied to the brake cylinders 10 and 11 to rebuild that lost by leakage. Should the brakes be released and the cylinders exhausted during the automatic operation just described, in restoring the leakage, the sudden drop in pressure while the disk 27 is off its seat will make a considerable difference in pressure on the upper and lower sides of the piston disk 37, causing it to be forced to its seat 36, and close the port therein. The stem 30 being down, no air can pass into chamber 33 through the passage 32 and the hole 31, but should the disk 27 become normally seated, these passage ways will become connected upon the raising of the stem 30 and the pressure will become equalized on opposite sides of the piston disk 37, which will leave the spring 38 free to operate and force the disk 37 off its seat 36 causing the port therein to become normally open. Also due to the sudden drop in pressure in the chamber 24 during exhaust of the brake cylinders, the initial pressure in the chamber 22 will push the disk 55 off its seat and exhaust through the

channel 54 and release the pressure upon the diaphragm 23, which would otherwise hold the disk 27 off its seat. After exhaust from the cylinders has taken place the various valves just described are again in normal position ready to be again operated and perform their functions when the brakes are again set by full active pressure, and the chamber 22 again becomes charged in the manner previously described. 70

While the supply valve with the disk 27, the check valve with the disk 45, the differential check valve with the disk 55 and the stop valve with the piston disk 37, with certain connecting channels just described, 75 have been shown in section as a compound valve within one casing for convenience, each of said valves might be isolated except for channel connections formed of piping and all might be correlated in the same relation apart from a common casing and be operative in the way described above. 80

In the system shown in Fig. 2 the compound valve 19^a is in all parts and functions correlated like those described above for 85 compound valve 19, except that the differential check valve is not used to release the air from the chamber 22. In this form of my invention I provide a check valve 60, which when open, exhausts the air in the 90 chamber 22 through the passage 21^a, the pipe 73, the passage 74, the chamber 69, the chamber 67 and the hole 75 to the atmosphere. This exhaust can take place pending either of the two positions of the engineer's 95 automatic brake valve 1^a known as the "full release" and the "running" positions. In either of these positions the handle 61 depresses the lever 63 causing the yoke 64 to force down the stem 65 and push the disk 100 70 off its seat, opening the valve to the atmosphere. 105

In Fig. 3 the handle 61 is drawn in full lines over the notch 81 and represents "full release" position of said handle. The 110 dotted position at 61^a shows the handle in "running" position over notch 80. As the handle 61 is moved in succession over the notches 77, 78, 79 to 80 it only engages the beveled end 63^a of the lever 63 as it passes 115 into position 61^a. For the positions of the handle over notch 77 known as "emergency application," over notch 78, known as "service application," and that over notch 79 known as "lap" position the handle 61 is 120 free from the lever 63 and the valve 60, by means of the spring 71, remains normally closed. Hence during the "lap," "service," or "emergency" positions of the handle any initial pressure stored in the control chamber 22 is there reserved for action upon the diaphragm 23, as described above in connection with Fig. 2, but when the brakes are released by bringing the handle 61 to "running" or "release" position the lever 63 is 125 130

depressed opening valve 60, releasing the pressure in the chamber 22.

Releasing means operated in connection with the triple valve 8 during exhaust from the brake cylinders might be substituted for either of those described in connection with Figs. 1 and 2 for releasing the pressure in the control chamber 22 during said exhaust.

Having described my invention I claim:—

- 10 1. A pressure maintaining system of devices in combination with an air brake cylinder and means for supplying fluid pressure, said system of devices consisting of, a valve mechanism having a variable pressure chamber connected with said cylinder and a pressure control chamber separated from said variable pressure chamber by a movable wall, there being a passage connecting said chambers, a check valve in said passage adapted to permit air to flow through said passage into said control chamber, pressure releasing means connected with said control chamber, a supply valve adapted to be operated by said movable wall, a stop valve between said supply valve and said means for supplying fluid pressure, said stop valve having a port in its seat and a disk adapted to close said port, there being a restricted opening through said disk, out of alinement with said port, means affording channels from said stop valve to said supply valve apart from the ports in the seats of said valves, and means adapted to close said channels during the opening of said supply valve.

2. In combination with an air brake cylinder and means for supplying fluid pressure, a pressure maintaining system of devices comprising a supplemental reservoir, a check valve between said means for supplying fluid pressure and said supplemental reservoir, a valve mechanism having two chambers separated by a movable wall, one of said chambers being connected with said cylinder, the other chamber being a control chamber, there being a passage connecting said chambers, a check valve in said passage adapted to permit air to pass into said control chamber, a supply valve adapted to be operated by said movable wall, pressure releasing means connected with said control chamber, means affording connections between said means for supplying pressure and said supply valve, and interposed means in said connections adapted to pass small quantities of air to replenish leakage in said cylinder and to shut off said air to said supply valve upon a sudden diminution of pressure in said cylinder.

3. In combination with an air brake cylinder and means for supplying fluid pressure, a pressure maintaining system of devices comprising a supplemental reservoir, a check valve between said means for supplying fluid pressure and said supplemental

reservoir, a valve mechanism having two chambers separated by a movable wall, one of said chambers being connected with said cylinder, the other chamber being a control chamber, there being a passage connecting said chambers, a check valve in said passage adapted to permit air to pass into said control chamber, a supply valve adapted to be operated by said movable wall, pressure releasing means connected with said control chamber, means affording connections between said means for supplying pressure and said supply valve, interposed means in said connections adapted to pass small quantities of air to replenish leakage in said cylinder and to shut off said air to said supply valve upon a sudden diminution of pressure in said cylinder, and means for equalizing pressure within said connections on either side of said interposed means upon the closure of said supply valve.

4. A pressure maintaining system of devices in combination with an air brake cylinder and means for supplying fluid pressure, said system of devices consisting of a valve mechanism having a variable pressure chamber connected with said cylinder and a pressure control chamber separated from said variable pressure chamber by a movable wall, there being a passage connecting said chambers, a check valve in said passage adapted to permit air to flow through said passage into said control chamber, a manually controlled release valve connected with said control chamber, a supply valve adapted to be operated by said movable wall, a stop valve between said supply valve and said means for supplying fluid pressure, said stop valve having a port in its seat and a disk adapted to close said port, there being a restricted opening through said disk, out of alinement with said port, means affording channels from said stop valve to said supply valve apart from the ports in the seats of said valve, and means adapted to close said channels during the opening of said supply valve.

5. A pressure maintaining system of devices in combination with an air brake cylinder, an engineer's automatic brake valve, and means for supplying fluid pressure, said system of devices consisting of, a valve mechanism having a variable pressure chamber connected with said cylinder and a pressure control chamber separated from said variable pressure chamber by a movable wall, there being a passage connecting said chambers, a check valve in said passage adapted to permit air to flow through said passage into said control chamber, pressure releasing means connected with said control chamber, said releasing means being actuated by said engineer's brake valve, a supply valve adapted to be operated by said movable wall,

a stop valve between said supply valve and said means for supplying fluid pressure, said stop valve having a port in its seat and a disk adapted to close said port, there being 5 a restricted opening through said disk, out of alinement with said port, means affording channels from said stop valve to said supply valve apart from the port in the seat of said valve, and means adapted to close 10 said channels during the said opening of said supply valve.

6. A pressure maintaining system of devices in combination with an air brake cylinder, and means for supplying fluid pressure, said system of devices consisting of a valve mechanism having a variable pressure chamber connected with said cylinder and a pressure control chamber separated from said variable pressure chamber by a movable wall, there being a passage connecting 15 said chambers, a check valve in said passage adapted to permit air to flow through said

passage into said control chamber, pressure releasing means connected with said control chamber, said releasing means being adapted to be normally closed during the restoration of pressure in said cylinder, a supply valve adapted to be operated by said movable wall, a stop valve between said supply valve and said means for supplying fluid 20 pressure, said stop valve having a port in its seat and a disk adapted to close said port, there being a restricted opening through said disk, out of alinement with said port, means affording channels from 25 said stop valve to said supply valve apart from the ports in the seats of said valves, and means adapted to close said channels during the opening of said supply valve.
